(57) **CLAIM**

The ornamental design for a secure full swing rack door hinge, as shown and described.

DESCRIPTION

FIG. 1 shows a perspective view of the design according to the invention.

FIG. 2 shows a rear view of the design according to the invention.

FIG. 3 shows a front view of the design according to the invention.

FIG. 4 shows a top view of the design according to the invention.

FIG. 5 shows a bottom view of the design according to the invention.

FIG. 6 shows a left side view of the design according to the invention; and,

FIG. 7 shows a right side view of the design according to the invention.
